UNITED STATES PATENT OFFICE.

JOHN G. GRAHAM, OF GRANITE CITY, ILLINOIS.

SHEET-METAL-DOUBLING MACHINE.

1,252,270.

Specification of Letters Patent.

Patented Jan. 1, 1918.

Application filed February 28, 1917. Serial No. 151,479.

To all whom it may concern:

Be it known that I, JOHN G. GRAHAM, a citizen of the United States, residing at Granite City, in the county of Madison and 5 State of Illinois, have invented a new and useful Improvement in Sheet-Metal-Doubling Machines, of which the following is a specification.

My invention relates to a machine for 10 doubling sheet-metal, and has for its object to provide a machine by which sheet-metal is readily and quickly doubled automatically for producing a pack of two or more sheets.

It consists in features of novelty as hereinafter described and claimed, reference being had to the accompanying drawing forming part of this specification, whereon,

Figure 1, is a vertical longitudinal section through my improved sheet-metal doubling 20 machine, omitting parts of the driving gear; Fig. 2, a top plan of the same; Fig. 3, a vertical transverse section through the foundation of the machine, omitting the floor-plate, and showing the machine in front end 25 elevation; Fig. 4, a similar view to Fig. 1, broken away, with the folding parts of the machine in different positions respectively; Fig. 5, a horizontal section through the shank and guides of the presser-plate and 30 its appendages forming parts of my invention, on line 5, 5, in Figs. 1 and 3; Fig. 6, a vertical cross section through a number of the folding parts of the machine, on line 6, 6, in Fig. 2; Fig. 7, an end view of the 35 same; Fig. 8, a top plan of the driving gear of the machine detached from the general views, and Fig. 9, a vertical section through the same taken longitudinally with the machine on line 9, 9, in Fig. 8.

Like letters and numerals of reference denote like parts in all the figures.

a represents a preferably, metal floor-plate on which the metal sheet 1 (represented by the heavy black line in Figs. 1 and 3) to 45 be doubled is laid. Beneath the floor-plate *a* is a bed 2 on which is fixed a block *b* having a channel or guideway 3 in central alinement, or thereabout, longitudinally with the metal sheet 1, and in which is adapted to 50 slide forward and rearward, a rectangular-shaped bar *c* having across its upper face a series of teeth 4 which are adapted to be engaged by preferably a toothed spur wheel *d* fixed above the bar *c* (hereinafter termed 55 rack) on a transversely arranged shaft *e*

which is mounted in suitable bearings 5 secured to the foundation of the machine beneath the shaft *e*. From the rear end portion of, and in the plane of the rack *c* extends an upwardly, and preferably, rearwardly inclined member *c'* which is formed at its upper end with a rearwardly projecting L-shaped offset *c''* having its vertical leg 6 projecting upward through the floor-plate *a* and bearing at its front side against 60 the rear end edge of the metal sheet 1 when the latter is in its initial position on the floor-plate *a* as seen particularly in Figs. 1 and 2. On the shaft *e* at a suitable and equal distance from each side of the longitudinal center of the rack *c* and clear of the longitudinal edges of the metal sheet 1, is fulcrumed and fixed one end of an arm or lever *f* which is inclined upward and forward from the shaft *e* toward the floor-plate *a* where it is fixed, preferably at its outer free end, to the corresponding end of a spindle 7, and on the spindle 7 in proximity and parallel thereto, is hinged by lugs 70 8 projecting therefrom, a flat rectangular-shaped bar *g* which extends lengthwise between, and at right angles to the arms *f*, and is free to move radially about its pivot or hinge 7, the bar *g* by which the metal sheet 1 is folded as hereinafter described, 75 being adapted to pass freely through a corresponding opening 9 therefor in the floor-plate *a* across which opening the front end portion of the metal sheet 1 extends, the upper face of the bar *g* bearing thereat 80 against the underside of the metal sheet 1 when the latter is in its initial position on the floor-plate *a* as seen in Figs. 1 and 2.

Longitudinally through the floor-plate *a* immediately over, and having its longitudinal edges clear of the corresponding sides of each arm *f*, is an opening 9' which extends rearward from the front opening 9 to a distance equal, or thereabout, to the travel of the arms *f* when swung by the 95 shaft *e* from the initial position of the bar *g* shown by full lines in Fig. 1, to its final position shown by dotted lines in Fig. 1, and by full lines in Fig. 4, and as herein-after more particularly referred to, the 100 openings 9' communicating at their rear ends with an opening 9² formed transversely through the floor-plate *a*, and communicating with a central longitudinal opening 9³ formed through the floor-plate *a* clear of 110

the sides of the offset c^2 of the rack c and extending rearward for a suitable distance from the opening 9^2 for allowing free movement of the offset c^2 to and fro according to 5 the varying lengths of the metal sheets to be doubled.

By the arrangement of the openings 9 , $9'$, 9^2 , and 9^3 , thus described it will be noted that, the consequently detached intervening 10 portion of the floor-plate a is secured to the surrounding portion of the latter in front, by a U-shaped bracket 10 (see particularly Fig. 1) which straddles the bar g beneath the floor-plate a and is fixed by one 15 leg to the front end of the detached portion and by its other leg to the adjacent surrounding portion of the floor-plate a , and similarly, at the rear end of the detached portion by U-shaped brackets $10'$ which 20 bridge the opening 9^2 at each side, and clear the opening 9^3 , whereby the intervening portion of the floor-plate a is firmly supported and held at the normal level of the floor.

h represents a shaft which is preferably 25 in alignment with, but separate from the shaft e , and is mounted in suitable bearings 11 secured beneath to the foundation. On the shaft h , which is preferably in the present case, fixed in the bearings 11, is mounted 30 loosely a spur wheel i which is adapted to engage with a vertically arranged toothed rack 12 formed on or fixed to one side of the upright shank 13 of a horizontal rectangular-shaped plate 14 which projects 35 longitudinally for a suitable distance from the upper end of the shank 13 above, and across the floor-plate a and the metal sheet 1 thereon, and carries the presser-plate k by which the folded portion of the metal sheet 40 1 is pressed downward upon the straight under portion thereof as hereinafter particularly referred to, the combined shank 13 and plate 14 forming an inverted L-shaped member.

45 The presser-plate k in the present case is formed along its longitudinal edges with upwardly projecting flanges 15 which are slidably in contact with the corresponding edges of the plate 14 and flanged inwardly 50 at the top so as to overlap the latter, a suitable space 16 being left between the plate 14 and the upper side of the presser-plate k , and in the space 16 are placed transversely a series of springs 17 preferably fixed to the 55 plate 14 and bearing at their free ends on the presser-plate k , whereby the presser-plate k is vertically yieldable and resilient when lowered upon the folded portion of the metal sheet 1.

60 For operating the machine various arrangements of mechanism driven by a single motor or otherwise may be used, the driving gear for this purpose in the present case consisting of a counter-shaft l arranged 65 parallel to the shafts e and h and rotatably

mounted in suitable bearings 18. On the shaft l is mounted loosely a spur pinion d' which is adapted to engage the spur wheel d on the shaft e , and a spur pinion i' adapted to engage the spur wheel i on the shaft h , 70 and on the shaft l is feathered a suitable clutch, such as a friction clutch m which is adapted to engage the pinion d' , and a similar clutch n adapted to engage the pinion i' , the clutches m and n being controlled by a 75 suitable system of levers, such as the levers m' , n' , which are connected to each other by a link o and the latter to a lever 19 having its outer free end adapted for engagement by a spur pinion 20 which is fixed to an upright spindle 21 projecting through the floor-plate a and provided above the latter with a handle 22 within reach of the operator.

p represents a motor (Figs. 2 and 8) having its shaft 23 at right angles to the counter-shaft l , and on the motor shaft 23 are loosely mounted two opposite bevel wheels 24, $24'$, which are adapted to engage with a bevel wheel 25 fixed on the adjacent end of the shaft l . 80

On the motor shaft 23 between the bevel wheels 24, $24'$, is feathered a clutch 26 which is adapted for engagement with either of the bevel wheels 24, $24'$, and controlled by a lever 26' or otherwise by any suitable 90 well-known means. On the fixed shaft h is also feathered a clutch 27 which is adapted for engagement with the spur wheel i for locking, and so preventing rotation of the latter by the tendency of the presser-plate k 100 and its appendages to descend by gravity when the spur wheel i is thrown out of gear with the driving mechanism in the operation of the machine. Or in lieu of the clutch 27 for this purpose, an ordinary pulley and 105 band brake may be used.

In operation, assuming the metal sheet 1 to be placed on the floor-plate a in its initial position as shown by the heavy black line in Figs. 1 and 3, and by ordinary full lines in Fig. 2, and that the motor shaft 23 is rotated in the direction of arrow 28 (Fig. 8) with the clutch 26 thrown into engagement with the bevel wheel 24, the bevel wheel 25 and with it the counter-shaft l will be rotated 110 in the direction of arrow 29, when the clutch m being thrown into engagement with the pinion d' by moving the operating handle 22 from its mid position as shown in Fig. 8 into the dotted position x , the spur wheel d and 115 its shaft e will be rotated in the direction of arrow 30 (Figs. 8 and 1) and in so doing will raise and swing the doubling bar g from its initial position seen in Fig. 1 as indicated by arrow 31, or so as to raise the 120 metal sheet 1 at its front end; simultaneously, the rack c with its offset c^2 engaging the metal sheet 1 at its rear end is moved forward by the spur wheel d in the direction of arrow 32, and in so doing causes the 125

metal sheet 1 to be moved forward along the floor-plate *a*, the combined movements of the doubling bar *g* and rack *c* from their initial positions shown by full lines in Fig. 5 to their final positions indicated by dotted lines in Fig. 1 and by full lines in Fig. 4, thereby causing the metal sheet 1 to be folded over on itself into the position and shape indicated by dotted lines in Fig. 1.

10 By then moving the handle 22 of the driving gear into the mid position as shown by full lines in Fig. 8, the clutch *m* will be disengaged from the pinion *d'* and the motor *p* being then stopped, the clutch 26 is disengaged from the bevel wheel 24 and thrown into engagement with the bevel wheel 24', the clutch *n* at the same time being thrown into engagement with the pinion *i'* by moving the handle 22 into the dotted position *y* 15 and the locking clutch 27 released from the spur wheel *i*; when the motor *p* being re-started, the bevel wheel 25, and with it the counter-shaft *l* and pinion *i'* will be rotated in the direction of arrow 33 (Fig. 8) or so 20 as to lower the members 13, 14 and with it the presser-plate *k* from its position shown by full lines in Figs. 1 and 3 on to the metal sheet 1 until the folded portion of the latter is flattened and pressed downward upon the 25 underlying portion thereof as shown in Fig. 30, thereby doubling the sheet or producing a pack for re-rolling, and in this connection it is to be noted that, by means of the springs 17 before described, the impact of the 35 presser-plate *k* upon the metal sheet 1 is cushioned.

The motor *p* being then again stopped, the clutch 26 is disengaged from the bevel wheel 24' and reengaged with the bevel wheel 24 40 which on re-starting the motor *p* causes the spur wheel *i* to be rotated in the opposite direction from arrow 33, or so as to raise the presser-plate *k* from the metal sheet 1 into its original position. The motor *p* is then 45 again stopped and the spur wheel *i* locked by the clutch 27, when by disengaging the clutch *n* from the pinion *i'* and reengaging the clutch *m* with the pinion *d'* the spur wheel *d* on re-starting the motor *p*, will be 50 rotated in the opposite direction to arrow 30, or so as to return the doubling bar *g* and rack *c* to their original position, when the doubled sheet 1 is removed.

In the meantime however, previous to re-starting the motor *p* and returning the parts 55 as last mentioned, the shearing blade *s* (see Figs. 1, 3, and 4) carried by the vertically arranged toothed racks 34 which are operated by the toothed pinions 35 fixed on a shaft 36 mounted in bearings 37 at the sides of the standard 38, is lowered and passing between the vertical leg 6 of the offset *c*² and the reinforced forward edge of the opening 9² shears or trims the irregular rear 60 end edges 39 of the doubled sheet 1, the

shearing mechanism referred to being of the ordinary well-known construction and therefore needing no further description.

I claim:

1. In a sheet-metal doubling machine, the combination of a floor adapted to support the said sheet, a rotatable shaft arranged beneath the floor transversely to the sheet, a toothed wheel fixed on the shaft, a toothed rack adapted to be engaged by the said wheel and having a suitable member adapted to bear against the rear end of the sheet, an arm fixed at one end to the shaft and adapted at its other end to bear against the underside of the sheet, means for rotating the shaft, and means for pressing and flattening the folded portion of the sheet on to the underlying portion thereof. 70

2. In a sheet-metal doubling machine, the combination of a floor adapted to support the said sheet, a rotatable shaft arranged beneath the floor transversely to the sheet, a toothed wheel fixed on the shaft, a toothed rack adapted to be engaged by the said wheel and slide longitudinally in a plane parallel to the floor, the said rack having a suitable member adapted to bear against the rear end of the sheet, an arm fixed at one end to the shaft at each side of the said wheel, a bar hinged to, and extending between the said arms at a suitable distance forward from the shaft, the said bar bearing thereat against the underside of the sheet, means for rotating the shaft, and means for pressing and flattening the folded portion of the sheet on to the underlying portion thereof. 85

3. In a sheet-metal doubling machine, the combination of a floor adapted to support the said sheet, a rotatable shaft arranged beneath the floor transversely to the sheet, a toothed wheel fixed on the shaft, a toothed rack adapted to be engaged by the said wheel and slide longitudinally in a plane parallel to the floor, the said rack having a suitable member adapted to bear against the rear end of the sheet, an arm fixed at one end to the shaft at each side of the said wheel, a bar hinged to, and extending between the said arms at a suitable distance forward from the shaft, the said bar bearing thereat against the underside of the sheet, means for rotating the shaft, a presser-plate, and means for lowering and raising the said plate on to and from the folded portion of the sheet respectively. 105

4. In a sheet-metal doubling machine, the combination of a floor adapted to support the said sheet, a rotatable shaft arranged beneath the floor transversely to the sheet, a toothed wheel fixed on the shaft, a toothed rack adapted to be engaged by the said wheel and slide longitudinally in a plane parallel to the floor, the said rack having a suitable member adapted to bear against the rear end of the sheet, an arm fixed at one 120

end to the shaft at each side of the said wheel, a bar hinged to and extending between the said arms at a suitable distance forward from the shaft, the said bar bearing thereat against the underside of the sheet, a shaft, a toothed wheel on the last named shaft, a presser-plate, a member adapted to carry and to lower and raise the said plate on to and from the folded portion of the

sheet respectively, a toothed rack carried 10 by the said member and adapted to be engaged by the last named wheel, and means for rotating the said wheels independently of each other.

JOHN G. GRAHAM.
